UNITED STATES PATENT OFFICE

SOCRATES H. CAPELIS, OF EL CERRITO, CALIFORNIA

DESIGN FOR AN AIRPLANE

Application filed February 15, 1932. Serial No. 42,876. Term of patent 14 years.

To all whom it may concern:

Be it known that I, SOCRATES H. CAPELIS, a citizen of the United States, residing at El Cerrito, in the county of Contra Costa and State of California, have invented a new, original, and ornamental Design for Airplanes, of which the following is a specification, reference being had to the accompanying drawings forming part thereof.

Fig. 1 is a plan view of the airplane.
Fig. 2 is a front elevation of the airplane.
Fig. 3 is a side elevation of the airplane.

I claim:

The ornamental design for an airplane as shown.

SOCRATES H. CAPELIS.
